UNITED STATES PATENT OFFICE.

JOSEPH S. DUNCAN AND HENRY E. HUBBARD, OF CHICAGO, ILLINOIS, ASSIGNORS TO
ADDRESSOGRAPH COMPANY, OF CHICAGO, ILLINOIS, A CORPORATION OF ILLINOIS.

RIBBON SPOOL.

Application filed August 26, 1925. Serial No. 52,503.

This invention relates to ink ribbon spools for use in connection with the ribbon mechanism of our companion application Serial No. 52,504, filed concurrently herewith, or 5 other ribbon mechanisms for which it is or may be adapted.

The object of the invention is to provide a ribbon spool of simple construction adapted to cooperate with mechanism for insuring reversal of operation of the ribbon and having means for fastening the ribbon securely to the spool and also acting as a driving element for cooperating with a driver to 10 revolve the spool.

15 The invention also has for its object to provide a simple method of manufacturing a spool of this character and for securing the ribbon thereto so that the ribbon cannot be replaced to use the spool again 20 after the original ribbon has been worn out.

Referring to the drawings, Figure 1 is a perspective view of a spool embodying the invention, showing a ribbon attached thereto.

25 Fig. 2 is an elevation of the driver which is more particularly described in our companion application referred to.

Fig. 3 shows the blank from which the spool is made, and

30 Fig. 4 shows the same blank provided with the engaging prongs.

Figs. 5, 6, 7 and 8 show progressive steps in forming the spool and securing the ribbon therein.

35 Fig. 9 is a plan view of the spool shown in Fig. 8.

Fig. 10 is an enlarged detail sectional view of a portion of a spool.

Fig. 11 shows one of the tools for forming 40 a prong.

Fig. 12 is a sectional view showing the spool on a bed and preparatory to punching the prongs.

Fig. 13 is a sectional view on line 13—13 45 of Fig. 12.

Fig. 14 is a sectional view showing the manner in which the openings are punched in the spool to secure the overlapping margins of the spool upon the ribbon.

50 Referring to the drawings the spool 15 is made in cylindrical form of thin sheet metal from a blank 16, which is provided with a plurality of slots 17 to receive the reversing tripper of the ribbon mechanism, as

55 application. In the embodiment of the invention illustrated here and in our companion application the tripper comprises three rollers (not shown) which are adapted to ride upon the ribbon wound spool until the ribbon is unwound therefrom, whereupon the rollers enter the slots 17 thereby tripping the mechanism to effect reversal of travel of the ribbon.

60 The spool blank is provided with a plurality of small prongs 18 along one marginal edge and these prongs are formed by the pointed ends 19 of a plurality of punches 20, Figs. 11, 13. The blank is arranged upon a bed 21 having a groove 22 between 65 gauges 23 and a shoulder 24 and the punches 13 are driven down upon the blank to punch out the prongs into the groove 22.

70 The blank is then bent into cylindrical form, as shown in Fig. 5, with the margin 24 having the prongs 18 underlying the margin 25, and the ribbon 26 is folded over upon itself at its end and a tool 27 is engaged with the fold to push the ribbon in between the overlapping margins, after which the 75 tool can be withdrawn without pulling out the ribbon, which becomes engaged with the prongs 18.

78 Then the spool is placed upon a mandrel 28 and the openings 29 are punched therein, 80 the material punched out forming projections 30, Fig. 10, which extend into the spool and are arranged in alignment lengthwise thereof. These openings 29 and the 85 projections 30 are formed by a plurality of 90 punches 31 which are driven through the overlapping margins 24, 25 and the interposed ribbon, there being a groove 32 in the mandrel to receive the ends of the punches and the ends of the projections 30, Fig. 14.

95 The punches have curved faces 31' which cause the projections 30 to curve inwardly and away from each other in a hook-like form, as shown more clearly in Fig. 10, thereby securely locking the margins of the 100 spool together upon the interposed spool of the ribbon and fastening the ribbon securely to the spool. These projections extend in a line lengthwise of the spool and constitute a driving element to engage the groove 32 in

105 the driver 33, which forms a part of the ribbon mechanism, and is driven to revolve the spool. This driver has peripheral grooves 34 to accommodate the rollers of the tripper, when the latter enter the slots 17.

It is desirable that provision should be made for insuring that the spools will always be arranged properly on the driver and for that purpose we provide the spool

- 5 with projections 35 at one end to engage a recess 36 in the driver. It will readily be understood that this arrangement permits the spool to be arranged on the driver right end to but prevents the spool being arranged 10 on the driver wrong end to, since the groove 32 in the driver is not of sufficient width to accommodate the projection 35.

This invention provides a spool as an article of manufacture which is adapted to operate with a tripper for reversing the travel of the ribbon, and it also provides a spool of simple construction, with the overlapping margins rigidly interlocked upon the interposed ribbon, to securely fasten the ribbon to the spool and with projections extending inwardly of the spool to interengage with a driver, whereby the spool is revolved. The invention is simple in construction, easy to manufacture and assemble, and the ribbon 25 is permanently engaged with the spool so that it cannot be removed and replaced.

We reserve the right to make all changes in the details of construction as fairly fall within the scope of the following claims.

30 We claim:

1. An ink ribbon spool formed from a blank of sheet metal having its side margins overlapped, the under margin having prongs struck up therefrom to receive and hold the 35 end of the ribbon when it is inserted between the margins, the upper margin being non-perforate.

2. A ribbon spool formed from a blank of sheet metal having its side margins overlapped, there being openings punched in one of said margins and the metal struck up thereby forming prongs, the opposite margin being imperforate.

40 3. An ink ribbon spool formed from a

blank of sheet metal having its side-margins 45 overlapped, a ribbon received there-between, and punch pricks securing said margins and interposed ribbon together.

4. An ink ribbon spool formed from a blank of sheet metal having its side margins 50 overlapped, there being openings punched in the under margin and the metal struck up thereby forming prongs, a ribbon received between said margins and held by said prongs, and punch pricks securing the margins 55 and interposed ribbon together.

5. A ribbon spool formed from a blank of sheet metal having its side margins overlapped, there being openings punched in the under margin and the metal struck up thereby forming prongs, a ribbon received between said margins and held by said prongs, and punch pricks securing the margins 60 and interposed ribbon together.

6. An ink ribbon spool formed from a 65 blank of sheet metal having its side margins overlapped to receive the ribbon therebetween, openings being punched through said margins and interposed ribbon, and the metal forced out to form said openings projecting 70 inwardly of the spool.

7. An ink ribbon spool formed from a blank of sheet metal having its side margins overlapped to receive the end of the ribbon therebetween, and projections punched inward from the overlapped margins and interposed ribbon and extending within the 75 spool in alignment lengthwise thereof.

8. An ink ribbon spool formed from a blank of sheet metal having its side margins overlapped to receive the end of the ribbon therebetween, and hook-shaped projections stamped from the overlapped margins and interposed ribbon and extending inward of the spool.

JOSEPH S. DUNCAN.
